METHOD OF LAPPING GEARS

Emil R. Gasser, Buffalo, N. Y., assignor to Farrel-Birmingham Company, Inc., Buffalo, N. Y., a corporation of Connecticut

Application December 3, 1945, Serial No. 632,352

1 Claim. (Cl. 51—287)

1

My present invention relates to a method of lapping gears and pinions of the spur, single helical and double helical types and aims to provide certain improvements therein.

Gear tooth contours as cut on a gear cutting or generating machine are composed of innumerable infinitesimal facets, and in order to eliminate these small inaccuracies of machining and produce smoother and more precise tooth contours, the gears are subjected to a lapping process.

In the past, gears have been lapped by merely running the mating gear and pinion together with a lapping compound between the toothed surfaces. More recent practice consists in lapping the gears with lapping dummies which are simple cast iron gears proportioned as to tooth form to give a certain lapping action when meshed with a gear or pinion to be lapped, and using a suitable lapping compound. More specifically, current practice consists in taking one dummy lapping pinion and meshing it with the subject gear to be lapped and then operating the two together for a certain length of time. After this, another dummy lapping pinion of somewhat different tooth proportions is meshed with the same subject gear and again operated for a certain length of time, usually the same as with the first dummy pinion. Finally, the subject gear that has been lapped is then meshed with the pinion that is normally supplied with the gear and given a so-called final lapping for a certain period of time.

It is a well known fact that if a gear and a pinion, whether it be a dummy lapping pinion or a regular pinion are operated together with an abrasive lapping compound, a hump will develop on the gear teeth at points known as the pitch points where no sliding action or but very little sliding action takes place during gear operation. This hump constitutes a distortion of the necessary involute shape that is so essential for quiet operation of gears and for proper load distribution on the tooth surfaces, and prior to the present invention complete elimination of the hump at the pitch points could not be satisfactorily accomplished by lapping action.

The present invention has for its primary object the elimination of the hump at the pitch points of gear teeth by a lapping operation. A further object is to substantially reduce the time consumed for the lapping operation as compared with prior practice. A further object is to accomplish the first two mentioned objects while maintaining the involute form of the teeth on the 50

2

subject gear being lapped and on the lapping dummies regardless of the duration of the lapping operation.

The foregoing and other objects not specifically enumerated are accomplished by operating two lapping pinions simultaneously in mesh with the subject gear to be lapped, the pitch circles of the lapping pinions being so proportioned to the operating pitch circles of the subject gear that the corresponding pitch points are at different pressure angles. The invention will be better understood from the detailed description which follows when considered in connection with the accompanying drawing which is illustrative of the method, and wherein—

Figure 1 is a diagrammatic side elevation of the arrangement of the subject gear to be lapped and the lapping pinions when carrying out the present invention.

Fig. 2 is an enlarged fractional side elevation showing the tooth action for high pressure angle lapping such as will be accomplished by the left hand lapping pinion of Fig. 1.

Fig. 3 is a view similar to Fig. 2 showing the tooth action for low pressure angle lapping such as will be accomplished by the right hand lapping pinion of Fig. 1.

In carrying out the method of the present invention a subject gear 10 to be lapped is shown in mesh with two dummy lapping pinions 11 and 12, the subject gear and the lapping pinions being mounted on spindles supported in bearings 13, 14 and 15, respectively. The bearings may be adjustably mounted upon a bed plate 16 or the like, and means (not shown) may be provided for driving the subject gear or the dummy pinions, as desired. In Fig. 1 of the drawings, in lieu of showing the teeth of the subject gear and the lapping pinions, there is merely shown the root circles, the engaging pitch circles and the addendum circles of said respective gears. The teeth relationship of the subject gear and the lapping pinions are, however, shown in Figs. 2 and 3. In the gear 10 and pinions 11 and 12, the root circles are designated 10a, 11a and 12a, and the addendum circles as 10b, 11b and 12b, respectively. The engaging pitch circle 11c of the lapping pinion 11 is shown as providing for low pressure angle engagement with the gear 10 and as being tangent to the engaging pitch circle 10c of the subject gear 10. The engaging pitch circle 12c of lapping pinion 12 is shown as providing for high pressure angle engagement with gear 10 and as being tangent to the engaging pitch circle 10d of the subject gear 10.

3

In Fig. 2 there is illustrated the relationship of the teeth on the lapping pinion 12 and the subject gear 10 whereby high pressure angle lapping is achieved. It will be noted that the addendum of the teeth on the lapping pinion is relatively greater than on the subject gear and provides an engaging pressure angle between the teeth of about 22°. In Fig. 3 the teeth relationship is such as to provide for low pressure angle lapping at a pressure angle of about 18°. These angles may differ in different gear lapping operations but it is preferable that the lapping pinions 11 and 12 are so proportioned with relation to the subject gear that the operating pressure angle of one lapping pinion with the subject gear is greater by approximately the same degree as the operating pressure of the other lapping pinion is less than the intended normal operating pressure angle of the subject gear when operating with its regular pinion (not shown). And so in the case illustrated in the drawings, the intended normal operating pressure angle of the subject gear with its regular pinion is approximately 20°, wherefore, when such a subject gear is operated in mesh simultaneously with pinions such as 11 and 12 with an abrasive lapping compound between the toothed surfaces, any hump which would normally build up at the pitch point of the teeth of the subject gear due to the high pressure angle lapping is immediately wiped clean by the low pressure angle lapping of the other pinion, and vice versa. Because of this action the tooth shapes of the lapping pinions and the subject gear being lapped maintain their original involute shape accuracy and in fact even improve themselves.

After the subject gear 10 and the lapping pinions 11 and 12 have been simultaneously operated in mesh with a lapping compound for a predetermined arbitrary length of time, the subject gear is given a final lapping treatment with the pinion, or a substantially identical pinion, that is normally supplied with the subject gear.

The lapping pinions are made as though they were regular gears in a conventional manner on gear cutting or generating machines, but for the purpose of economy I prefer to make them of cast iron.

From the foregoing detailed description it will be appreciated that with the present invention the objects recited in the opening statement of this specification are accomplished. These may again be summarized as follows:

4

(a) The time consumed for lapping is reduced to about one-half that required where only a single lapping pinion is used.

(b) The tooth shape of the subject gear and the lapping gears is maintained in involute form regardless of the duration of the lapping operation.

(c) The lapping pinions or dummies as they are termed tend to retain their original involute shape much longer than when used in lapping by the old method and can therefore be used without recutting to lap more gears than if they had been used singly.

In the foregoing description and in the claim it is to be understood that the terms gear and pinion are used synonymously and that either may be substituted for the other without affecting the scope of the invention.

What I claim is:

20 The method of lapping a gear to improve its tooth surface contour, said method comprising operating a subject gear to be lapped in mesh completely across the width of its teeth simultaneously with two lapping pinions with a lapping compound between the meshed toothed surfaces, providing an operating pressure angle between the teeth of one lapping pinion with the teeth of the subject gear which is greater than the intended normal operating pressure angle of said subject gear, and an operating pressure angle between the teeth of the other lapping pinion with the teeth of the subject gear which is lesser than the normal intended operating pressure angle of the subject gear, and so choosing said greater and lesser operating pressure angles that they differ from the normal intended operating pressure angle of the subject gear, by approximately the same degree.

EMIL R. GASSER.
